UNITED STATES PATENT OFFICE.

ALBERT KÜNZLER, OF CONSTANCE, GERMANY.

BUCKLE.

No. 896,644.

Specification of Letters Patent. Patented Aug. 18, 1908.

Application filed August 12, 1907. Serial No. 388,877.

To all whom it may concern:

Be it known that I, ALBERT KÜNZLER, a subject of the German Emperor, residing at Constance, in the Grand-Duchy of Baden, Germany, have invented certain new and useful improvements in Buckles, of which the following is a specification.

This invention relates to a tongueless buckle for fastening belts, straps and the like. 10 The invention substantially consists in arranging two slidable bars in a buckle-frame and connecting the said bars by means of a toggle-joint so that they can be thrust apart and made to grip the strap by pressing the 15 same against members of the frame.

A construction embodying the invention is illustrated in the annexed drawing in which Figure 1 is a rear view of the buckle and Fig. 2 a longitudinal section thereof. Fig. 3 illustrates in section the buckle and strap in operative position.

The buckle-frame *a* has a cross-bar *b* for the permanent attachment of one end of the strap *i*. The two longer bars of the frame 25 have grooves *c*, in which two bars *d* and *e* are slidable but not rotatable. These bars *d* and *e* are connected to each other by two hinge-plates *f* and *g* and a rectangular link *h*, forming a toggle-joint. The toggle-joint and bars 30 *d* and *e* can be conjointly displaced in the frame, and the said bars can also be thrust apart or moved toward each other by actuating the toggle-joint. For fastening the strap the toggle-joint is extended, and for unfastening it the joint is flexed.

When the three members *g*, *h* and *f* are extended there is between the end-bars of the

frame and the bars *d* and *e* only sufficient space for the tight passage of the strap. When the joint is flexed, as shown in Fig. 2, 40 the strap can easily pass through the spaces *m* and *n*. For fastening the strap, pressure is exerted on the bulging part *k* thereof, and the free end of the strap is by this means pushed through the space *n*, but at the same 45 time the toggle-joint is extended, and when the knuckle of the joint has been pushed through the frame the strap is firmly gripped at *m* and *n*. For unfastening the straps the toggle-joint is flexed by pressing the knuckle 50 outwards. To further diminish the risk of accidental slipping, the surfaces of the short hinge-joint *f* and frame *a* may be ribbed, spiked or made rough at the part where the strap is gripped between the said hinge-joint 55 and frame.

What I claim as my invention and desire to secure by Letters Patent of the United States is:—

A tongueless buckle comprising in combination a frame, two independently slidable bars movable to and from the ends of the frame and a toggle-joint connecting said bars and adapted by its extension to thrust them apart towards the ends of the frame for the 60 purpose of gripping the strap or the like to be fastened.

In witness whereof I have signed this specification in the presence of two witnesses.

ALBERT KÜNZLER.
